UNITED STATES PATENT OFFICE.

EDUARD LEISSNÈR, OF NEW YORK, N. Y., ASSIGNOR TO LEISSNÈR & LOUIS,
OF SAME PLACE.

DESIGN FOR WALL-PAPER.

SPECIFICATION forming part of Design No. 12,508, dated October 4, 1881.

Application filed August 25, 1881. Term of patent 3½ years.

To all whom it may concern:

Be it known that I, EDUARD LEISSNÈR, of New York, in the county and State of New York, have invented a new and original Design for Wall-Paper, of which the following is a specification.

This invention relates to a new and original design for wall-paper and similar fabrics; and it consists in the novel grouping and configuration of parts hereinafter more fully described.

The accompanying photograph illustrates a face view of a wall-paper having my new design.

15 F is a group composed of a flower-like figure, *f*, above a small rosette, below which is a branch, *n*, bearing berry-like fruits in bunches. Another branch, *i*, with similar fruit, projects to the left of the branch *n*, while to the right 20 of said branch *n* projects downwardly a branch, *h*, carrying star-like flowers. The group *G* ap-

pears to grow out of a stem, *e*, having clusters of berries, and its upper figure is a cluster, *g*, of star-like flowers, and below the same a cluster, *k*, of similar star-like flowers. The stems 25 of the floral groups *h* and *k* appear to intermingle.

The groundwork of this design has series of undulating lines, and also at times horizontally-placed dashes, which impart to it an apparent indefiniteness, through which, nevertheless, the character of the grouping can be freely ascertained.

I claim—

The design for wall-paper, consisting of the 35 group *F*, having figures *f* *h* *i* *n*, and group *G*, having figures *e*, *g*, and *k*, substantially as shown.

EDUARD LEISSNÈR.
